UNITED STATES PATENT OFFICE

133,826

DESIGN FOR A BANNER OR THE LIKE

Mark Cooney, San Francisco, Calif., assignor of one-half to Leo Y. Booharin, San Francisco, Calif.

Application June 8, 1942, Serial No. 107,151

Term of patent 14 years

To all whom it may concern:

Be it known that I, Mark Cooney, a citizen of the United States, residing at 175 Parnassus Street, San Francisco, in the county of San Francisco and State of California, have invented a new, original, and ornamental Design for a Banner or the like, of which the following is a specification, reference being had to the accompanying drawing, forming part thereof.

The figure is a plan view of a banner or the like, showing my new design.

I claim:

The ornamentation for a banner or the like, as shown.

MARK COONEY.
